[57] ABSTRACT

A simultaneous radio communication system comprising first and second radio stations adapted to transmit first and second radio waves of the same radio channel and receive the transmitted second and first radio waves, in which the first and second radio waves are interrupted waves interrupted in opposite phases at the same period; the on-state periods of the transmitted first radio waves include time compressed third information of first information to be transmitted; the on-state periods of the transmitted second radio waves include time compressed fourth information of second information to be transmitted; and the first and second radio stations have means for time expansion of the time compressed fourth and third information from the second and first transmitted radio waves to obtain sixth and fifth information corresponding to the second and first information respectively.

SIMULTANEOUS RADIO COMMUNICATION SYSTEM BETWEEN TWO STATIONS

BACKGROUND OF THE INVENTION

1. Field of the Invention

This invention relates to a radio communication system, and more particularly to a simultaneous radio transmission and reception system which is adapted so that information is simultaneously transmitted and received between two radio stations.

2. Description of the Prior Art

With conventional simultaneous radio communication systems of this kind, two radio stations simultaneously transmit radio waves of different radio frequency channels so that two radio frequency channels are required for simultaneous information transmission and reception between two radio stations. Therefore, it has been desired to realize a system which employs only one radio frequency channel for simultaneous information transmission and reception between two radio stations.

SUMMARY OF THE INVENTION

Accordingly, the present invention is to provide a novel simultaneous radio transmission and reception system adapted for simultaneously transmitting and receiving information between two stations with one radio frequency channel.

BRIEF DESCRIPTION OF THE DRAWINGS

FIG. 1 is a block diagram showing one example of the simultaneous radio transmission and reception system of this invention;

FIGS. 2 and 3 are respectively a schematic diagram showing one example of each of a time base compressor and a time base expander employed in the example of FIG. 1 and a side view showing their principal parts;

FIGS. 4 and 5 are signal arrangement diagrams, for explaining the present invention;

FIG. 6 is a connection diagram illustrating another example of the time base compressor;

FIG. 7 shows signal arrangements, for explaining the time base compressor of FIG. 6;

FIG. 8 is a connection diagram illustrating another example of the time base expander; and

FIG. 9 shows signal arrangements, for explaining the time base expander of FIG. 8.

DESCRIPTION OF THE PREFERRED EMBODIMENTS

With reference to the drawings, one example of this invention will hereinafter be described as being applied to a simultaneous radiotelephone system.

In FIG. 1, reference characters TR1 and TR2 indicate generally radio stations of the following construction.

An aural signal SA from an aural signal source 1 is supplied to a time base compressor 2, from which is derived an aural signal SB produced by time base compression of the aural signal SA.

The time base compressor 2 has the following construction. As shown in FIGS. 2 and 3, it comprises a magnetic recording and reproducing device 7 having a rotary magnetic disc 4 coupled with a rotation driving source 3a, a fixed magnetic head HA mounted on the

free end of a fixed support arm 5 and a rotary magnetic head HB mounted on the free end of a rotary support arm 6 coupled with a rotation driving source 3b. In this case, the fixed magnetic head HA is disposed in contact with or adjacent to the rotary magnetic disc 4 with its air gap GA aligned with a radial reference line OA-LA passing through a rotary shaft 8 of the rotary magnetic disc 4 in such a manner that the air gap GA may form a rotational track FA of a width a on the rotary magnetic disc 4 and that, when viewed from the rotary magnetic disc 4, the gap GA may form a cubic rotational track QA of a predetermined width a' about the rotary shaft 8. While, the rotary magnetic head HB is mounted on the rotary support arm 6 so that its air gap GB is aligned with a radial line OB-LB passing through a rotary shaft 9 of the rotary support arm 6. The rotary shaft 9 of the rotary support arm 6 is disposed eccentrically of the rotary shaft 8 of the rotary magnetic disc 4 with the rotary magnetic head HB disposed in contact with or adjacent to the rotary magnetic disc 4 on a line diametrically opposite to the reference line OA-LA in such a manner that, when viewed from the rotary magnetic disc 4, the air gap GB of the rotary magnetic head HB may form a cubic rotational track QB of a width b' with its outer periphery crossing the cubic rotational track QA of the fixed magnetic head HA in its region of the width a' at those areas where the fixed magnetic head HA does not lie and that the air gap GB may form a rotational track FB of a width b on the rotary magnetic disc 4 without collision of the rotary magnetic head HB with the fixed magnetic head HA. In this case, however, the center of the rotational track FB of the air gap GB of the rotary magnetic head HB bears such a relation to that of the track FA of the gap GA of the fixed magnetic head HA that the track FB is displaced towards the outer periphery of the track FA on the opposite side from the fixed magnetic head HA.

The rotary magnetic disc 4 and the rotary magnetic head HB are respectively driven clockwise and anti-clockwise at the same rotational period T by the driving sources 3a and 3b which are controlled by a synchronizing signal PS derived from a synchronizing signal generator circuit 11 described later. Under such condition, when the aural signal SA is supplied to the fixed magnetic head HA, it is recorded on the rotary magnetic disc 4 while forming the same track as the rotational track FA and it is reproduced by the rotary magnetic head HB and the reproduced signal is obtained as the time base compressed aural signal SB. The time base compressed aural signal SB is derived from the aural signal SA by the magnetic recording and reproducing device 7 in the following manner.

The rotational track FA formed by the fixed magnetic head HA on the rotary magnetic disc 4 is equally divided in a clockwise direction into sections D₁, D₂, D₃ and D₄. Assume that the rotary magnetic disc 4 is driven at a constant speed with the rotational period T from an instant t₁ when the beginning of the section D₁ lies on the reference line OA-LA. Instants when the beginnings of the sections D₂, D₃, D₄, D₁, D₂, . . . sequentially cross the reference line OA-LA from the instant t₁ are taken as t₂, t₃, t₄, t₅, . . . (the time between t₁ and t₂, between t₂ and t₃, between t₃ and t₄, . . . is T/4). Assume that the aural signal SA is obtained from the instant t₁ as shown in FIG. 4A. Signal portions of the signal SA between the instants t₁ and t₂, between t₂ and t₃, between t₃ and t₄, . . . are taken as S₁, S₂, S₃, . . . respectively.

tively. It will be apparent that the signal portions $S_1, S_2, S_3, S_4, S_5, S_6, \dots$ are sequentially recorded by the fixed magnetic head HA in the sections $D_1, D_2, D_3, D_4, D_1, D_2, \dots$ on the track FA of the rotary magnetic disc 4.

Assume that the signal portions $S_1, S_2, S_3, S_4, S_5, S_6, \dots$ are sequentially recorded in the sections $D_1, D_2, D_3, D_4, D_1, D_2, \dots$ on the track FA of the rotary magnetic disc 4, that the fixed magnetic head HA is not present, that the center OB of the rotary shaft 9 of the rotary magnetic head HB lies on that OA of the rotary shaft 8 of the rotary magnetic disc 4, that the radius of the track formed by the air gap GB of the rotary magnetic head HB on the rotary magnetic disc 4 is equal to that of the track FA formed by the fixed magnetic head HA and that the rotary magnetic head HB lies at a rotational position spaced 90° apart from the reference line OA-LA in an anticlockwise direction at the instant t_1 . In such a case, the rotary magnetic head HB scans the sections D_2 and D_3, D_4 and D_1, D_2 and $D_3, \dots$ of the track FA on the rotary magnetic disc 4 between the instants t_1 and t_2 , between t_2 and t_3 , between t_3 and t_4 , so that a reproduced signal (identified by SB') derived from the rotary magnetic head HB is obtained as a signal having such an arrangement as shown in FIG. 4B which consists of a non-signal portion, a signal portion S_1' reproduced from the signal portion S_1 , continuous signal portions S_2' and S_3' reproduced from the continuous signal portions S_2 and S_3 , the signal portion S_1' reproduced from the signal S_1 , the continuous signal portions S_2' and S_3' reproduced from the continuous signal portions S_2 and S_3 , continuous signal portions S_4' and S_5' reproduced from the continuous signal portions S_4 and S_5 , continuous signal portions S_6' and S_7' reproduced from the continuous signal portions S_6 and S_7 , the continuous signal portions S_4' and S_5' reproduced from the continuous signal portions S_4 and S_5 , the continuous signal portions S_6' and S_7' reproduced from the continuous signal portions S_6 and S_7 , ... Accordingly, assuming that the aural signal SA is continuously recorded on the track FA on the rotary magnetic disc 4, that the fixed magnetic head HA is not provided and that the center OB of the rotary shaft 9 of the rotary magnetic head HB lies on that OA of the rotary magnetic disc 4, the signal SB' derived from the rotary magnetic head HB is obtained as a signal which has a time base one-half times that of the aural signal SA and is time-compressed. The foregoing description has been made on the assumption that the aural signal SA is continuously recorded on the track FA on the rotary magnetic disc 4, that the fixed magnetic head HA is not provided and that the center OB of the rotary shaft 9 of the rotary magnetic head HB lies on that OA of the rotary magnetic disc 4 but, if the fixed magnetic head HA is provided in the above case, the rotary magnetic head HB collides with the head HA and the above-described aural signal SB' cannot be obtained. With the construction of this invention described previously, however, the center OB of the rotary shaft 9 of the rotary magnetic head HB is eccentric from that OA of the rotary magnetic disc 4 as described previously, so that the rotary magnetic head HB does not collide with the fixed magnetic head HA. Further, due to this eccentricity, the track FB of the rotary magnetic head HB deviates away from that FA of the fixed magnetic head HA on the side of the head HA, and consequently the aural signal SA derived from the rotary magnetic head HB is

obtained as the signal SB' which partly drops out in periods between the instants t_3 and t_5 , between t_7 and t_9 , between t_{11} and t_{13} , . . . , as described above. However, even if such dropout exists, such dropout periods are not used, and hence does not present any problem as will become apparent from the following description. Since the air gap GB of the rotary magnetic head HB is not aligned with a line extending radially from the center of the rotary shaft 8 of the rotary magnetic disc 4, the amplitude of the signal SB also fluctuates between the instants t_1 and t_3 , between t_5 and t_7 , between t_9 and t_{11} , . . . but the amplitude fluctuation can be made negligibly small by minimizing the distance between the centers OA and OB of the rotary shafts 8 and 9. If, however, the amplitude fluctuation presents any problem, it is sufficient to frequency or phase modulate the signal SA previously, supply the frequency or phase modulated signal to the fixed magnetic head HA and insert an amplitude limiter in the system of the rotary magnetic head HB.

The foregoing description has clarified that the time compressed aural signal SB is derived from the aural signal SA by means of the time base compressor 2. The aural signal SB is supplied to a transmitting circuit 16 and thereby converted into radio waves RS of a predetermined frequency channel, which are transmitted through a transmitting antenna 17. In this case, the transmitting circuit 16 is controlled by an interrupted control signal PQ derived from an interrupted control signal generating circuit 18 which is controlled by the synchronizing signal PS as is the case with the driving sources 3a and 3b of the time base compressor 2, so that the radio waves RS are obtained in the form of interrupted wave. Namely, the interrupted control signal generating circuit 18 derives therefrom such an interrupted control signal PQ as shown in FIG. 4C which is controlled by the synchronizing signal PS to have a width of one-half of the rotating period T of the rotary magnetic disc 4 and the rotary magnetic head HB of the above-described time base compressor 2 and turn on at the aforementioned instants $t_1, t_5, t_9, \dots$. The transmitting circuit 16 is controlled by the interrupted control signal PQ, so that the radio waves RS from the transmitting circuit 16 are transmitted as interrupted waves (shown by the signal arrangement) such as shown in FIG. 4D which are interrupted by the interrupted control signal PQ. In this case, since the reproduced signal portion S_1' and the continuous reproduced signal portions $S_2' \text{ to } S_5', S_6' \text{ to } S_9', \dots$ of the aural signal SB derived from the time base compressor 2 are arranged in the duration periods of the radio waves RS, that is, in the periods between the instants t_1 and t_3 , between t_5 and t_7 , between t_9 and t_{11} , . . . , the interrupted radio waves RS include the contents of the aural signal SA without dropout and overlapping of the contents. Accordingly, with the construction described above, the aural signal SA is time compressed and transmitted as the interrupted radio waves RS without dropping out and overlapping the contents of the aural signal SA.

The foregoing has clarified one example of the transmission system of each of the radio stations TR1 and TR2. The following will describe one example of their reception system. The reception system is designed such that the transmitted interrupted radio waves RS obtained as described above are received by a receiving antenna 21 and supplied to a receiving circuit 22 to derive therefrom an aural signal SC such as depicted in

FIG. 4E which is interrupted in response to the interruption of the transmitted waves RS. In this case, since the interruption of the transmitted waves RS is caused by the interruption of the interrupted control signal PQ shown in FIG. 4C, it will be apparent that the aural signal SC is obtained as an interrupted signal of a signal arrangement including the reproduced signal portion S_1' in the latter half period between the instants t_2 and t_3 , the continuous reproduced signal portions S_2' to S_5' between the instants t_5 and t_7 , the continuous reproduced signal portions S_6' to S_9' between the instants t_9 and t_{11} , ...

The interrupted aural signal SC thus obtained is supplied to a time expander 23 to derive at its output terminal 24 a continuous aural signal SD produced by time expansion of the interrupted aural signal SC. In this case, the time expander 23 is formed with exactly the same magnetic recording and reproducing device as that 7 for the above-described time base compressor 2, so that it is not illustrated. In this case, however, the aural signal SC is supplied to the rotary magnetic head HB. Thus, it will be seen that the aural signal SD derived from the fixed magnetic head HA of the magnetic recording and reproducing device 7 is obtained on the same time base and with the same contents as the aural signal SA in the following manner. Namely, the interrupted aural signal SC shown in FIG. 4E is derived from the aural signal SA shown in FIG. 4A and supplied to the rotary magnetic head HB unlike in the time base compressor 2 and recorded on the rotary magnetic disc 4 and the recorded signal is reproduced by the fixed magnetic head HA. In this case, however, the aural signal SD is obtained from the instant t_5 as depicted in FIG. 4F.

The foregoing has clarified one example of the construction of each of the radio stations TR1 and TR2 in the case where the time base compressor 2 and the time expander 23 are each formed with the magnetic recording and reproducing device 7 described previously with regard to FIGS. 2 and 3. However, the time base compressor 2 and the time base expander 23 may also be of such constructions as will hereinbelow be described in connection with FIGS. 6 to 9.

FIG. 6 illustrates another example of the time base compressor 2, in which the aural signal SA from the aural signal source 1 is supplied to sampling circuits B_1 , B_2 , B_3 and B_4 shown to be four in all for the sake of brevity. While, a pulse-like synchronizing signal PS such as shown in FIG. 7A, which is derived from the above-described synchronizing signal generator circuit 11, is applied to a synchronous oscillator 51 to derive therefrom a pulse CP1 having a period one-fourth of that T of the synchronizing signal PS as depicted in FIG. 7B, which is supplied to a pulse distributing circuit 52 together with the synchronizing signal PS. The pulse distributing circuit 52 is adapted to derive at its output terminals U_1 , U_2 , U_3 and U_4 pulses P_1 , P_2 , P_3 and P_4 such as shown in FIGS. 7C₁, 7C₂, 7C₃ and 7C₄ which have the period T and are sequentially displaced T/4 apart in phase. In this case, the pulse P_1 is in-phase with the synchronizing signal PS. The pulses P_i ($i = 1, 2, 3$ and 4) are supplied as sampling pulses to the sampling circuits B_i . Thus, the aural signal SA is sampled with the sampling pulses P_i and the sampled outputs are stored in memory circuits D_1 , D_2 , D_3 and D_4 which are reset each time the pulses P_1 , P_2 , P_3 and P_4 are obtained respectively. Accordingly, if instants at which the pulse

CP1 is obtained are taken as t_1 , t_2 , . . . and if signal portions of the aural signal SA at the instants t_1 , t_2 , . . . are taken as S_1 , S_2 , S_3 , . . . respectively, the memory circuits D_i store signal portions S_i , $S_{(i+4)}$, $S_{(i+8)}$ in periods between instants t_1 and $t_{(i+4)}$, between $t_{(i+4)}$ and $t_{(i+8)}$, between $t_{(i+8)}$ and $t_{(i+2)}$, . . . as illustrated in FIGS. 7D_i.

Further, the memory circuits D_1 , D_2 , D_3 and D_4 have connected thereto read-out circuits F_1 , F_2 , F_3 and F_4 respectively. While, the pulse CP1 derived from the synchronous oscillator 51 is supplied to a frequency multiplier circuit 53 to derive therefrom a pulse CP2 of a period T/8 such as depicted in FIG. 7E, which is applied to a pulse distributing circuit 54 together with the synchronizing signal PS. The pulse distributing circuit 54 derives at its output terminals Q_1 , Q_2 , Q_3 and Q_4 pulses X_1 , X_2 , X_3 and X_4 of a period T/2 such as shown in FIGS. 7F₁, 7F₂, 7F₃ and 7F₄ which are sequentially displaced T/8 apart in phase and has a pulse width T/8 respectively. In this case, the pulse X_1 is in-phase with the synchronizing signal PS. The pulses X_i are supplied as gate signals to the read-out circuits F_i . Consequently, if the instants at which the pulse CP2 is obtained are taken as t_1 , t_1' , t_2' , . . . , the read-out circuit F_1 derives therefrom an output such as in FIG. 7G₁ which includes the signal portions S_1 , S_1 , S_5 , S_5 , . . . in the periods between the instants t_1 and t_1' , between t_3 and t_3' , between t_5 and t_5' , between t_7 and t_7' , . . . , the read-out circuit F_2 derives therefrom an output such as depicted in FIG. 7G₂ which includes the signal portions S_2 , S_2 , S_6 , S_6 , . . . in the periods between the instants t_3' and t_4 , between t_5' and t_6 , between t_7' and t_8 , between t_9' and t_{10} , . . . , the read-out circuit F_3 an output such as shown in FIG. 7G₃ which includes the signal portions S_3 , S_3 , S_7 , S_7 , . . . in the periods between the instants t_4 and t_4' , between t_6 and t_6' , between t_8 and t_8' , between t_{10} and t_{10}' , . . . and the read-out circuit F_4 derives therefrom an output such as shown in FIG. 7G₄ which includes the signal portions S_4 , S_4 , S_8 , S_8 , . . . in the periods between the instants t_4' and t_5 , between t_6' and t_7 , between t_8' and t_9 , between t_{10}' and t_{11} , ...

The outputs thus derived from the read-out circuits F_1 to F_4 , shown in FIGS. 7G₁ to 7G₄ are combined together to provide a time compressed aural signal SB such as depicted in FIG. 7H which includes the signal portions S_1 , S_1 , S_2 , S_3 , . . . in the periods between the instants t_1 and t_1' , between t_3 and t_3' , between t_3' and t_4 , between t_4 and t_4' , ...

Such an aural signal SB as shown in FIG. 7H, which is obtained with the time base compressor 2 of the above-described construction, is applied to the aforementioned transmitting circuit 16 and the transmitting circuit 16 is controlled with an interrupted signal PQ from the interrupted control signal generator circuit 18 such as shown in FIG. 7I which turns off between the instants t_1 and t_3 , between t_5 and t_7 , . . . and turns on between the instants t_3 and t_5 , between t_7 and t_9 , . . . , thereby providing transmitted radio waves RS (shown by an arrangement of the aural signal) such as depicted in FIG. 7J which are obtained from the time base compressed aural signal SB.

It will be understood that when the transmitted waves RS thus obtained are received by the receiving circuit 22 through the antenna 21, the receiving circuit 22 derives therefrom a time compressed aural signal SC of such an aural signal arrangement as depicted in FIG. 9A.

FIG. 8 illustrates another example of the time expander 23 for time expansion of the aural signal SC thus obtained, in which parts corresponding to those in FIG. 6 are identified by the same reference numerals and in which the aural signal SC is applied to gate circuits G_1 to G_4 . While, the synchronous oscillator circuit 51 supplied with a synchronizing signal PS of FIG. 9B (which is displaced 180° apart in phase from the synchronizing signal PS of FIG. 7A as will become apparent from the following description) derives therefrom a pulse CP1 such as depicted in FIG. 9C and the frequency multiplier circuit 53 derives therefrom a pulse CP2 such as shown in FIG. 9D, which is supplied to a pulse distributing circuit 54' together with the synchronizing signal PS, thus providing at its output terminals Q_1 , Q_2 , Q_3 and Q_4 pulses X_1' , X_2' , X_3' and X_4' of the period T such as shown in FIGS. 9E₁, 9E₂, 9E₃ and 9E₄ which have a pulse width T/8 and are sequentially displaced T/8 apart in phase. The pulses X_i' are applied as gate signals to the gate circuits G_i . The signal portions S_1 , $S_{(i+4)}$, $S_{(i+8)}$, . . . of the aural signal SC pass through the gate circuits G_i and are stored in the memory circuits D_i which are reset by the pulses X_i' . Accordingly, the memory circuit D_1 stores therein the signal portions S_1 , S_5 , . . . in the periods between the instants t_3 and t_7 , between t_7 and t_{11} , . . . as shown in FIG. 9F₁, the memory circuit D_2 stores therein the signal portions S_2 , S_6 , . . . in the periods between the instants t_3' and t_7' , between t_7' and t_{11}' as depicted in FIG. 9F₂, the memory circuit D_3 stores therein the signal portions S_3 , S_7 , . . . in the periods between the instants t_4 and t_8 , between t_8 and t_{12} , . . . as shown in FIG. 9F₃ and the memory circuit D_4 stores therein the signal portions S_4 , S_8 , . . . in the periods between the instants t_4' and t_8' , between t_8' and t_{12}' , . . . as depicted in FIG. 9F₄.

Further, the read-out circuits F_i are connected to the memory circuits D_i . While, the pulse CP1 from the synchronous oscillator 51 is supplied to the pulse distributing circuit 52' to derive at its output terminals U_i pulses P_i' of the period T such as shown in FIGS. 9G_i which have a pulse width T/4 and are sequentially displaced T/4 apart in phase and these pulses P_i' are applied as gate signals to the read-out circuits F_i . Consequently, the read-out circuit F_1 derives therefrom an output such as shown in FIG. 9H₁ which includes the signal portions S_1 , S_5 , . . . in the periods between the instants t_3 and t_4 , between t_7 and t_8 , . . ., the circuit F_2 derives therefrom an output such as depicted in FIG. 9H₂ which includes the signal portions S_2 , S_6 , . . . in the periods between the instants t_4 and t_5 , between t_8 and t_9 , . . ., the circuit F_3 derives therefrom an output such as shown in FIG. 9H₃ which includes the signal portions S_3 , S_7 , . . . in the periods between the instants t_5 and t_6 , between t_9 and t_{10} , . . . and the circuit F_4 derives therefrom an output such as depicted in FIG. 9H₄ which includes the signal portions S_4 , S_8 , . . . in the periods between the instants t_6 and t_7 , between t_{10} and t_{11} , . . .

The outputs thus derived from the read-out circuits F_1 to F_4 , shown in FIGS. 9H₁ to 9H₄, are combined together to provide a continuous aural signal SD such as depicted in FIG. 9I that the aural signal SC is time expanded and which includes the signal portions S_1 , S_2 , S_3 , . . . in the periods between the instants t_3 and t_4 , between t_4 and t_5 , between t_5 and t_6 , . . .

The foregoing has clarified the construction of one example of the radio stations TR₁ and TR₂. In the present invention, the interrupted radio waves RS (herein-

after identified by RS1 and RS2) obtained with the radio stations TR₁ and TR₂ are of the same frequency channel and the transmitted radio waves RS1 and RS2 are synchronized with each other so that they are interrupted in opposite relation to each other and the radio stations are designed such that the interrupted radio waves RS transmitted from the antenna of each station may be received by its receiving circuit 22. To this end, in each of the radio stations TR₁ and TR₂, one part of the radio waves RS received by the receiving circuit 22 or the output SC therefrom is supplied to the aforementioned synchronizing signal generator circuit 11 to derive therefrom a synchronizing signal PS having detected the interrupting positions of the transmitted waves RS and the synchronizing signal PS is applied to the time base compressor 2, the time base expander 23 and the interrupted control signal generator circuit 18 to control their driving synchronously, as described previously. Further, an interrupted control signal generator 25, which is identical with that 18 for the transmitting circuit 16, is connected to the receiving circuit 22 and this circuit 25 is also controlled by the synchronizing signal PS to provide the same interrupted control signal PQ' described previously with regard to FIGS. 4C and 7I. In this case, however, the synchronizing signals PS in the radio stations TR₁ and TR₂ are displaced 180° apart in phase, as will be seen from the arrangements shown in FIGS. 7A and 9B. The interrupted control signals PQ and PQ' derived from the interrupted control signal generators 18 and 25 are interrupted in opposite phases. Further, the interrupted control signals PQ obtained with the interrupted control signal generator circuits 18 in the two radio stations respectively are also interrupted in reverse phases.

The foregoing has described the construction of one example of this invention. With such a construction, where the interrupted radio waves RS1 obtained in the radio station TR₁ are of such a signal arrangement as depicted in FIG. 5A, the interrupted radio waves RS2 in the radio station TR₂ are obtained in such a relation that they are in the on-state in the off-state periods of the interrupted radio waves RS1 as shown in FIG. 5B and the receiving circuits 22 of the both radio stations TR₁ and TR₂ operate in the on-state periods of the interrupted radio waves RS2 and RS1 respectively. Further, since the transmitted radio waves RS1 and RS2 contain the contents of the aural signals SA in the radio stations TR₁ and TR₂ respectively (where the time base compressor 2 shown in FIGS. 2 and 3 is employed, the transmitted radio waves contains the entire contents of the aural signals SA and where the time base compressor 2 of FIG. 6 is used, the radio waves contain the sampled contents of the aural signals), the aural signals SA of the radio stations TR₂ and TR₁ can simultaneously obtained in the radio stations TR₁ and TR₂. The present invention uses one radio frequency channel common to the two radio stations, and hence has such a great feature that the demand for simultaneous transmission and reception of aural signals between two radio stations with one radio frequency channel can be satisfactorily filled.

Although the present invention has been described as being applied to the simultaneous radiotelephone system, the invention is also applicable to the case where other desired information is simultaneously transmitted and received between two radio stations.

It will be apparent that many modifications and variations may be effected without departing from the scope of the novel concepts of this invention.

I claim as my invention:

1. A simultaneous radio communication system between first and second radio stations, each of said first and second radio stations comprising:
  - a. a continuous aural signal source;
  - b. a synchronizing signal generator;
  - c. a time base compressor controlled by a synchronizing signal from said synchronizing signal generator to compress a first continuous aural signal from said continuous aural signal source to provide a time base compressed aural signal;
  - d. a first interrupted control signal generator controlled by the synchronizing signal from said synchronizing signal generator to generate a first interrupted control signal;
  - e. a transmitting circuit controlled by the first interrupted control signal from said first interrupted control signal generator to convert the time base compressed aural signal from said time base compressor into an interrupted radio wave of a predetermined frequency channel;
  - f. a transmitting antenna for transmitting the interrupted wave from said transmitting circuit;
  - g. a receiving antenna for receiving the interrupted radio wave transmitted from said transmitting antenna of the other radio station;
  - h. a second interrupted control signal generator controlled by the synchronizing signal from said synchronizing signal generator to generate a second interrupted control signal;
  - i. a receiving circuit for converting the interrupted radio wave from said receiving antenna into an interrupted aural signal; and
  - j. a time base expander controlled by the synchronizing signal from said synchronizing signal generator

to expand the interrupted aural signal from the receiving circuit to provide a second continuous aural signal; in which said synchronizing signal generator of each of said first and second radio stations is adapted to obtain the synchronizing signal from the interrupted aural signal derived from said receiving circuit; the synchronizing signal is composed of pulse waves indicative of the instants when the interrupted aural signal is put in its on-state or/and off-state; the first and second control signals derived from said first and second control signal generators of each of said first and second radio stations are rectangular waves opposite in phase to each other and the first control signals derived from said first control signal generators of said first and second radio stations are opposite in phase to each other, whereby the interrupted radio waves obtained in said first and second radio stations bear such relationship that the on-state period of one of them corresponds to the off-state period of the other and the interrupted aural signals obtained in said first and second radio stations bear such relationship that the on-state period of the former corresponds to the off-state period of the latter; said time base compressor of each of said first and second radio stations is adapted so that, in the on-state period (or the off-state period) of the first interrupted control signal, the time base compressed aural signal derived from said time base compressor may be obtained as a signal produced by time base compressing all the components of the first continuous aural signal without any dropout and overlapping thereof; and said time base expander of each of said first and second radio stations is adapted so that the second continuous aural signal derived therefrom may have the same content as the first continuous aural signal.
